UNITED STATES PATENT OFFICE.

JOHN W. ERHARDT, OF NEW YORK, N. Y.

HAT PROTECTOR.

Application filed May 9, 1925. Serial No. 29,006.

The main object of this invention is to provide a protector for hats, particularly straw hats. The invention utilizes a piece of material impervious to water which is 5 worn over the hat in rainy weather and prevents the same from becoming damaged.

Another object is to provide a hat protector having means thereon for draining the water from the hat rearwardly on the 10 protector so that no water drips in front of the face of the wearer.

The above and other objects will become apparent in the description below, in which characters of reference refer to like-named 15 parts in the drawing.

Referring briefly to the drawing, Figure 1 is a perspective view, showing the hat protector as applied to the hat.

Figure 2 is a bottom plan view of a hat 20 having the protector mounted thereon.

Figure 3 is an end elevational view of Figure 2.

Figure 4 is a cross sectional view of Figure 2.

Referring in detail to the drawing, the 25 numeral 10 indicates the crown of the usual type of straw hat. This crown is encircled by a brim 11 which is of the same material and integral with the crown. The upper 30 surfaces of the brim and the side wall and roof 12 of the crown are exposed to the rain during a storm. As the material of the usual type of straw hat is damaged and bent, or in other ways misspaced by coming in 35 contact with the water, a hat protector is provided which covers these surfaces and also partly covers the bottom of the brim. This hat protector consists of a wall 13 which encircles the wall of the crown and is 40 an integral part of a roof 14 which covers the roof 12 of the crown 10. The wall 13 of the hat protector has a flange-like extension 15 projecting outwardly around its entire edge and this extension forms a covering 45 over the upper surface of the brim 11 of the hat. The outer edge of this extension is bent downwardly at 16 to provide a covering for the edge of the brim and then continues as a flap 17 which rests upon the underside of the brim 11 of the hat and is

adapted to completely enclose both sides of the brim so that no water may trickle upon the material forming the straw hat. The straw hat protector is provided with a ridge which completely encircles its edge and 55 passes from the bottom flap 17 at a position intermediate its length to the upper extension 15 around the edge 16 of the hat. At the forepart of the hat protector, the ridge indicated by the numeral 18 projects upwardly from the surface of the extension 15 and courses around the front of the hat protector where at its ends it drains about the edge 16 at positions 19 and 20 and then follows the rim of the edge around the remaining portion of the flap 17, the ridge 60 which projects from the flap 17 being indicated by the numeral 21.

The usual manner of wearing hats is to 70 tilt the same slightly forwardly. When a straw hat of the type illustrated in the application is tilted forwardly and is enclosed by a hat protector, such as shown, the drops of rain which would fall thereon would tend to drain off toward the front 75 of the hat and fall in front of the face. This is prevented by the ridge 18 which projects from the flange-like portion 15 at the front of the hat and serves as a baffle leading the water on the hat along the ridge 80 until either of the positions 19 or 20 are arrived at. At either of these positions, the course of the water is deflected and flows downwardly to ultimately drip from the hat at the sides of the head. Should water drip 85 on the rear edge of the hat protector, the water would flow toward the head were the rear portion of the ridge 21 eliminated. This ridge 21 deflects the natural flow of water so that it drains off at either of the 90 positions 19 and 20.

I claim:

A hat protector comprising a crown cover formed of a single piece of material, a flange encircling said crown cover for covering the upper surface of the brim of a hat, a flap integral with said flange for covering the under side of the hat brim, a marginal ridge extending parallel to the outer edge of approximately one half the front sur- 100

face of the flange, said ridge projecting upwardly from the upper surface of said flange, an additional ridge extending around the rear half of the lap of said cover and intermediate ridges joined to the ridge on the flange extending outwardly passing around the edge of the material covering the brim and then joining the ridge on the

lap, the ridge on the flange deflecting the water from the front to the sides of the hat ¹⁰ and the ridge on said lap causing the water to drain around said ridge to the rear of the hat.

In testimony whereof I affix my signature.

JOHN W. ERHARDT.
